UNITED STATES PATENT OFFICE.

FRANK R. MOORE, OF UPPER DARBY, PENNSYLVANIA.

GRINDING HEAD OR ATTACHMENT.

Application filed January 10, 1928. Serial No. 245,665.

My invention relates to a new and useful improvement in a grinding attachment for electrical or compressed air motors or the like, and it relates more particularly to a 5 novel grinding attachment which presents a substantially plane moving abrasive surface.

My invention consists of a suitable housing having mounted therein a main driving shaft and a main driving roll carried thereby, 10 said driving shaft being adapted to be connected with a source of power such as the shaft of an electric motor or a compressed air motor, or to be connected to a flexible shaft, of any suitable form, and a pair of suitably 15 aligned idle rolls, and an abrasive belt of a continuous character, passing over said driving roll and idle roll.

For the purpose of illustrating my invention I have shown in the accompanying 20 drawings one form thereof which is at present preferred by me, since the same has been found in practice to give satisfactory and reliable results, although it is to be understood that the various instrumentalities of which 25 my invention consists can be variously arranged and organized and that my invention is not limited to the precise arrangement and organization of the instrumentalities as herein shown and described.

30 In the accompanying drawing in which like reference characters indicate like parts:

Figure 1 represents a front elevation of the grinding attachment embodying my invention.

35 Figure 2 represents a vertical section on line 2—2 of Figure 5.

Figure 3 represents a perspective view of one of the idle shaft supporting yokes.

Figure 4 represents a side elevation of the 40 grinding attachment of my invention.

Figure 5 represents a section on line 5—5 of Figure 1.

Figure 6 represents a side elevation of one of the frame plates.

45 Figure 7 represents a side elevation of the opposed frame plate.

Figure 8 represents a side elevation of the stationary belt guide.

Figure 9 represents a section on line 9—9 50 of Figure 8.

In Figure 1 I have represented in dotted lines a source of motive power such as an electric motor, compressed air motor, or the like, to which the grinding attachment 2 of my 55 novel construction is adapted to be applied.

The attachment of my novel construction

includes two generally parallel and spaced frame members of plates 3 and 4, respectively, which are maintained in spaced relation to each other by the transverse spacing members 5 and 6, which are preferably formed integrally with one of the two plates, as for instance, the plate 3. The opposed plate is detachably secured to the spacing members 5 and 6 by means of bolts 7 extending through 60 corresponding holes 8 in the plate 4 and anchored in the corresponding threaded openings 9 in the spacing members 5 and 6.

65 The frame plate 4 is provided with a hollow boss 10 at its upper part, through which the main driving shaft 11 passes.

70 The boss 10 may be either plain as shown in Figures 1 and 2 or it may be provided with any suitable threaded or flanged means or devices, whereby it may be detachably secured to the housing of an electric motor, compressed air motor, or the like.

75 The boss 10 is provided with an enlarged bore 12, within which a thrust ball bearing 13 and a radial ball bearing 14 are provided.

80 The frame plate 3 is provided with a corresponding bore 15 in alignment with the bore 12 in which a corresponding ball bearing 16 is disposed. The main driving shaft 11 is carried by the inner races 17 and 18 of the ball bearings 14 and 16, respectively. The shaft 11 is provided with a flange 19 which bears against the thrust bearing 13, thereby to prevent any outward displacement of the shaft 11.

85 The driving roll 20 is carried by the shaft 11 and is keyed thereto by means of the key 21. The main driving roll 20 is preferably made of a light metal such as aluminum, and is provided with the two outer flanges 22 and 23 and a uniform covering or shell 24 of a resilient material such as rubber, or the like. The shafts 25 and 26 carried at the two lower corners of the frame are parallel to the shaft 11 and are positioned with respect to the 90 same as the base apices of an isosceles triangle.

95 The shaft 25 extends through corresponding holes 27 and 28 in the frame plates 3 and 4, respectively, and is secured therein by means of the locking nuts 29 threaded onto the ends of the shaft. The idle roll 30 may be either journalled directly upon the shaft 25 or may be carried by suitable ball bearings intermediate said shaft and the roll.

100 The idle roll 31 is likewise carried by the shaft 26, either journalled directly upon the

same or carried by suitable ball bearings intermediate said shaft 26 and roll 31.

The shaft 26, however, is carried in the bifurcated ends 32 of a supporting yoke 33, comprising the transverse member 34 from the two parallel members 35, which are slidably mounted in a pair of corresponding inclined channels 36 cut in the inner face of each of the frame plates 3 and 4, as shown in Figures 5, 6 and 7.

The shaft 26 extends through elongated slots 37 so as to permit an adjustment of the same. The yoke 33 is provided with a pair of opposed lugs or handle members 38 projecting laterally on each side thereof and extending through the elongated apertures 37 whereby said sliding yoke 33, together with the shaft 26 and roll 31 may be moved outwardly for purposes of adjustment.

Lock nuts 38 threaded on each of the opposed ends of the shaft 26 serve to lock the shaft 26 in the adjusted position.

A lower stationary guide member 39 is provided between the two idle rolls 30 and 31 for the purpose of supporting the span of the abrasive belt intermediate said two idle rolls, thereby to cause said abrasive belt to travel in a straight line between said rolls. The guide 30 is provided with a plane bottom surface 40 and an inclined upper surface 41, which is so related to the incline of the channels 36, that when the shaft 26 is withdrawn upwardly in the channels 36 and slots 37, the roll 31 will clear the upper surface 41 of the guide 39.

The guide 39 is provided with two upwardly extending terminal supporting brackets 42, which are secured to the lower edges of the two opposed frame plates 3 and 4, by a series of screws 43.

A handle member 44 is carried by an offset bracket 45 secured to the frame plate 4, in a position substantially in the center of the roll 20.

A shield or cover 46 is hingedly secured to the frame plate 4, by means of the pivot 47.

The abrasive belt 48 extends around the driving roll 20 and the idle rolls 30 and 31, and is guided by the flanges 22 and 23 of the driving roll 20.

The upper edge 49 of the frame plate 3 is lower than the corresponding edge of the frame plate 4 and is substantially in alignment with the edge of the flange 22.

When it is desired to remove the abrasive belt 28 from the machine, or when it is desired to put a new one on the same, it is merely necessary to withdraw or retract the shaft 26. In this retracted position of the shaft 26 the abrasive belt is sufficiently slack so as to slip right over the top of the frame plate 3.

To tighten up on the abrasive belt 48 it is merely necessary to move the shaft 26 on the outermost position and then to lock the same in said position.

Having thus described my invention what I claim as new and desire to secure by Letters Patent, is:—

1. A grinding attachment of the character stated, comprising a pair of spaced frame members, a driving shaft extending transversely of the upper part of said frame members, journalled therein and extending through one of said frame members, a driving roll carried by said driving shaft, a shaft extending transversely of the lower part of said frame members, an idle roll carried thereby, a guiding channel in the lower part of each of said frame members, a shaft supporting yoke slidably mounted in said guiding channels, a shaft carried by said guiding yoke, a second idle roll carried by said shaft, an abrasive belt extending around said driving roll and said pair of idle rolls, and means to lock said last named shaft in any adjusted position.

2. A grinding attachment of the character stated, comprising a pair of spaced frame members, a driving shaft extending transversely of the upper part of said frame members, journalled therein and extending through one of said frame members, a driving roll carried by said driving shaft, a shaft extending transversely of the lower part of said frame members, an idle roll carried thereby, a guiding channel in the lower part of each of said frame members, a shaft supporting yoke slidably mounted in said guiding channels, a shaft carried by said guiding yoke, a second idle roll carried by said shaft, an abrasive belt extending around said driving roll and said pair of idle rolls, means to lock said last named shaft in any adjusted position, and a stationary guide carried by said frame members intermediate said two idle rolls, adapted to support the span of the abrasive belt intermediate said two idle rolls.

FRANK R. MOORE.
